UNITED STATES PATENT OFFICE.

WILLIAM ESTY, OF LACONIA, NEW HAMPSHIRE.

DESIGN FOR A YOKE FOR AUTOMATIC FIRE-EXTINGUISHERS.

SPECIFICATION forming part of Design No. 26,255, dated November 10, 1896.

Application filed October 12, 1896. Serial No. 608,684. Term of patent 14 years.

To all whom it may concern:

Be it known that I, WILLIAM ESTY, a citizen of the United States, residing at Laconia, in the county of Belknap and State of New Hampshire, have invented and produced a new and original Design for a Yoke or Frame for an Automatic Fire-Extinguisher, of which the following is a specification, reference being had therein to the accompanying drawings.

Figures 1 and 2 are views at right angles to each other of a yoke or frame showing my design.

The leading features of my design are the approximately oval shape or form of the yoke or frame, the arms 1 thereof springing from an intermediate portion of the length of the cylindrical head portion 2, and at first curv-

ing outwardly and downwardly and then approaching and joining the enlargement or hub-like portion 3, the axis of the head portion 2, that of the hub-like portion 3, and the longer axis of the yoke being coincident.

Having thus fully described my design, what I claim, and desire to secure by Letters Patent, is--

The design for the yoke or frame of an automatic fire-extinguisher, substantially as shown.

In testimony whereof I affix my signature in presence of two witnesses.

WILLIAM ESTY.
